(57) **CLAIM**

I claim the ornamental design for a scanner, as shown and described.

DESCRIPTION

FIG. 1 is a left elevational view of a scanner showing my new design;

FIG. 2 is a right elevational view thereof;

FIG. 3 is a top plan view thereof;

FIG. 4 is a bottom plan view thereof;

FIG. 5 is a front elevational view thereof;

FIG. 6 is a back elevational view thereof; and,

FIG. 7 is a top right perspective view thereof.

The broken lines and unshaded portions contained within broken lines depict unclaimed features of the scanner that form no part of the design claim but are shown for illustrative purposes.
